EDWIN S. MAULSBY, OF RIDGEWOOD, NEW JERSEY, ASSIGNOR TO UNDERWOOD TYPE-WRITER COMPANY, OF NEW YORK, N. Y., A CORPORATION OF DELAWARE.

TYPE-WRITING MACHINE.

1,214,570.

Specification of Letters Patent.

Patented Feb. 6, 1917.

Application filed December 17, 1913. Serial No. 807,177.

To all whom it may concern:

Be it known that I, EDWIN S. MAULSBY, a citizen of the United States, residing in Ridgewood, in the county of Bergen and State of New Jersey, have invented certain new and useful Improvements in Type-Writing Machines, of which the following is a specification.

My invention relates to appliances for 10 typewriting machines, for rotating the platen to line-space or advance various work forms, such as cards, envelopes, bills, and the like.

A feature of the invention is the provision 15 of a handle or driver for rapidly rotating the platen and bringing it to the same position each time the driver is actuated, said driver, however permitting independent forward rotation of the platen, so that a work-piece 20 may be placed in the machine and fed to printing position while said driver remains at rest, and after being written upon in the usual manner, may be ejected from the machine by actuating the driver to the limit of its movement in one direction. 25 The driver may be then spring-returned to normal position, independently of the platen.

The device is particularly adapted for 30 use in writing *seriatim* upon work members, such as envelopes, cards, bills, invoices, or other work forms whose length will permit a work member to be placed on the platen, written upon, and removed from the platen without turning the platen through more 35 than one complete rotation.

The driver may be loosely mounted on 40 the platen axle, and its movement in both directions limited by stops, one of which is preferably adjustable to vary the forward limit of throw of the driver. The driving connection between the driver and platen may be effected by means of a dog on the driver, adapted to engage a detent or tooth 45 connected to the platen. Said tooth may be formed on a disk fixed to the platen axle in the path of said dog, so that when the driver is rotated forward to eject a work member the dog will engage said tooth and carry the platen forward to a position determined by the adjustable stop. The driver 50 when released is automatically returned by a spring, and before its return movement is completed, the dog is cammed out of the path of the tooth. The parts are now in 55 their normal position of rest, ready to re-

ceive a card or other work member. When the latter is placed on the machine and the platen rotated in the usual manner to bring the work member to printing position, the tooth rotating with the platen is carried 60 beyond the driver, which during such rotation remains at rest. After the printing has been completed the driver is rotated, independently of the platen during its initial movement, but at an intermediate position, varying with the extent the platen has been rotated, the driver engages said 65 tooth and carries the platen forward while the driver is completing its forward or active stroke, thereby ejecting the work member. 70 The platen is now at its starting position, having made a complete rotation, and the driver when released is also spring-returned to starting position.

The platen at each cycle moves through 75 a fixed distance, shown in the drawings to be preferably an exact entire revolution; and this cycle is repeated for every envelop, card or work-piece. Each cycle or complete revolution of the platen is performed in instalments; the initial instalment being performed by the line-spacing mechanism, which gives the platen step-by-step movements *ad libitum*; and the final instalment being performed by the driver. During the 80 initial instalments, the platen advances independently of the driver, and hence moves away from the driver; but upon operating the driver, it overtakes the platen and gives the latter the final instalment of its revolution; the driver being arrested when the platen exactly completes its cycle. Hence, 85 the typewritten envelop or card too small to reach around the platen can be discharged from the feed rolls automatically by simply 90 turning the driver as far as it will go.

Other features and advantages will hereinafter appear.

In the accompanying drawings, Figure 1 is a perspective view showing the carriage 100 of an Underwood typewriting machine with the present invention attached thereto. Fig. 2 is a part sectional end elevation view of the same, and showing a work member in position to be written upon. Fig. 3 is a 105 similar view, but with the driver rotated to the limit of its forward movement, the work member as shown being carried beyond the feed rolls into position to be removed from the machine. Fig. 4 shows the driver 110

thrown forward to position the platen preparatory to placing a work member thereon. Fig. 5 is a sectional front elevation view of the invention. Fig. 6 is a disassembled view of the parts of the attachment. Fig. 7 is a view similar to Fig. 2, but showing a roll mounted on the platen frame, from which a web is fed over the platen.

A rotary platen 1 is fixed to the platen 10 axle 2 journaled in the ends of a platen frame 3, said ends united by an inclined paper table or shelf 4 at the rear of the platen. The platen may be rotated, either by the usual hand wheels 5 fixed on the ends of the 15 platen axle, only one of which hand wheels appears, however, or by the line-space mechanism comprising a ratchet wheel 6 adapted to be driven by a pawl 7 on a slide 8 actuated by a line-space lever 9, the slide and lever being returned by a spring 10, and the platen held in its actuated position by the usual spring detent 10a.

A card or other work member 11 may be placed on the table 4 and fed forward between the platen and the rear and front feed rolls 12 and 13, by a hand wheel 5 or the line-space mechanism. After the card has been typewritten upon, the platen may be further rotated to eject the card by means 20 of a driver 14, herein shown as comprising an arm extending radially from a disk 15 loosely mounted on the platen axle 2, said arm provided with a handle 16. The driving connection between the driver 14 and the platen is effected by means of a detent or 25 tooth 17 formed on a disk 18 fixed to the platen axle, said tooth projecting into the path of a dog 19 carried by the driver. Said dog is slidably mounted on the driver 14, so that it may be retracted into position to 30 permit the detent 17 to pass it when the platen is rotated forward from the position shown, for example, in Fig. 7.

The dog 19 is mounted on the outer face 45 of the driver 14 and is provided with a neck 20 which extends through and is slidable in a slot 21 in the driver, a guide plate 22 on the inner face of the driver being connected to said neck and forming an abutment for 50 a spring 23 between said plate 22 and the driver for yieldingly holding the dog 19 in the path of the detent 17. The backward or return rotation or stroke of the driver 14 is limited by a stop 24 which may be provided 55 on a stationary disk 25 loosely mounted on the platen axle and held against rotation, as by means of an adjustable connecting link 26 between the disk 25 and the platen frame. The forward or active rotation or stroke of the driver 14 is limited by 60 an adjustable stop 27 which may be carried by a disk 28 loose on the platen axle, the stop being shown as a pin slidably mounted in a tube 29 and adapted to enter any one of 65 a series of openings 30 formed in the disk

25. A finger-piece 31 connected to the stop pin 27 permits the latter to be retracted against the pressure of a holding spring 32 housed within the tube 29, whereby said stop may be adjusted to any position and 70 locked in such position by the pin 27 entering an opening 30.

It will thus be seen that the driver 14 is adapted to oscillate through a variable arc, the amplitude of oscillation being determined by the adjustment of the forward stop 27. The driver is manually rotated in a forward direction until it engages the stop 27, and then having been released, is spring-returned to its initial position, Fig. 2, as by 80 means of a coil spring 33 connected at its outer end to the driver and at its inner end to a hub of the stationary disk 25. The dog 19 on the driver runs in close proximity to the periphery of the disk 18, whereby the 85 dog is in position to pick up the detent 17 as the driver moves forward, and to carry the platen forward with the driver to the Fig. 3 position. As the driver completes its return movement, the dog is cammed outward by a cam surface 34 on the disk 25, whereby when the platen is further rotated in positioning a subsequent work member, the detent 17 is permitted to move past the dog. 95

The operation may be reviewed as follows: The driver may be first rotated forward to the Fig. 4 position to bring the platen to initial position, such operation being required only as a preliminary to running a series of cards or other work members through the machine. Fig. 1 shows the parts in their normal position of rest ready to receive a card or other work member. The card is placed on the machine and fed forward as usual between the platen and the feed rolls 12 and 13, the platen being rotated, for example, by a hand wheel 5. The card is then typewritten upon in the usual manner, and then the driver 14 is swung forward from its position (Fig. 2) against the stop 24 to the Fig. 4 position against the forward stop 27. During this forward or active rotation of the driver the dog 19 thereon engages the detent 17, the position of the latter when thus engaged depending on the distance the card has been rotated over the platen during its introduction and the writing thereon. 110

As the driver completes its forward or active stroke, the detent 17 and with it the platen, are carried up to the Fig. 4 position. The card 11 is thus carried beyond the feed rolls, as shown in Fig. 3, ready to be removed from the machine. The platen is 125 now in its initial position, having made just one complete revolution.

The throw of the driver varies with the position of the forward stop 27. The extent to which the throw of the driver 14 130

may be shortened by adjusting the stop 27, is determined by the distance that the platen is rotated in introducing the work member and completing the writing thereon. That is, the rotation of the platen prior to the actuation of the driver 14 for ejecting the work member must be at least sufficient to carry the detent 17 from its normal position, Fig. 1, to a point beyond the dog 19 so that the latter may pick up the detent when the handle 16 is operated.

In Fig. 7, a roll 35 is mounted on the platen frame and may comprise either a series of printed forms or may be a web of blank paper for use either alone or in conjunction with bills or other work forms individually fed to the machine. If said web consists of a series of forms, said forms may be equal in length to the circumference of the platen, whereby at each operation of the driver 14 a new form will be brought into proper position to be typewritten upon; or if such forms are used in conjunction with disconnected forms or work members, the placing of a work member in position to be written upon, will also automatically position a printed form of the web. The roll 35 may also comprise a tally strip for use in the usual manner.

30 Variations may be resorted to within the scope of the invention, and portions of the improvements may be used without others.

Having thus described my invention, I claim:

35 1. The combination with a revoluble platen, of means for giving the same successive mechanically limited rotations, including a driver normally disconnected from the platen; a stop against which said driver normally rests during the advance rotation of the platen; means for giving the platen initial advance movements independently of the driver; means for automatically connecting said driver, during its active stroke, to said platen at any point to which the latter may have been advanced independently of the driver, so as to drive the platen forwardly a variable distance necessary to complete the forward rotation thereof through such mechanically limited distance; and a stop separate from the first-named stop for arresting the active stroke of said driver.

2. The combination with a revoluble platen, of means for giving the same successive mechanically limited rotations, including a driver normally disconnected from the platen; a stop against which said driver normally rests during the advance rotation of the platen; means for giving the platen initial advance movements independently of the driver; means for automatically connecting said driver, during its active stroke, to said platen at any point to which the latter may have been advanced independently

of the driver, so as to drive the platen forwardly a variable distance necessary to complete the forward rotation thereof through such mechanically limited distance; and a stop separate from the first-named stop for 70 arresting the active stroke of said driver, said stops being relatively adjustable.

3. The combination with a platen, of means for giving the platen in instalments a rotation through a fixed, predetermined distance, including a driver having an active stroke or movement of definite extent; a stop against which said driver normally rests; said platen being movable away from the driver while the latter is stationary, and means for enabling said driver to overtake the platen and thereafter positively rotate the platen throughout the final instalment of its said rotation.

4. The combination with a revoluble platen, of means for rotating the same in instalments through a fixed cycle, comprising step-by-step line-spacing mechanism, a crank for rotating the platen through its final instalment, a dog driven by said crank and normally withdrawn, a tooth fixed to the platen to be engaged by said dog for driving the platen, means dependent upon the movement of the crank for projecting the dog, a stop for arresting the platen and crank with the platen in a predetermined rotative position at the completion of the cycle, a spring for returning said crank to normal position while the platen remains stationary, and means for automatically withdrawing the dog upon the return of the crank to normal position, so that said tooth may, during the ensuing step-by-step line-feed of the platen, pass by said dog in a position to be reengaged thereby at the next driving operation of the crank.

5. The combination with a revoluble platen, of means for rotating the same in instalments through a fixed cycle, comprising step-by-step line-spacing mechanism, a crank for rotating the platen through its final instalment, a dog driven by said crank and normally withdrawn, a tooth fixed to the platen to be engaged by said dog for driving the platen, means dependent upon the movement of the crank for projecting the dog, a stop for arresting the platen and crank with the platen in a predetermined rotative position at the completion of the cycle, a spring for returning said crank to 110 normal position while the platen remains stationary, and means for automatically withdrawing the dog upon the return of the crank to normal position, so that said tooth may, during the ensuing step-by-step line-feed of the platen, pass by said dog in a position to be reengaged thereby at the next driving operation of the crank, said crank or resting stop being adjustable to vary the extent of throw of the crank.

6. In a typewriting machine, the combination with a revoluble platen, of means for advancing the same through successive cycles, each consisting of a complete revolution, and for mechanically determining the point of completion of each cycle, comprising line-by-line feeding mechanism for giving the platen its initial movements from the starting point, a driver at rest during the advancing of the platen by said line-spacing mechanism, a tooth or lug rotating with the platen past said driver during such line-spacing movements, means to couple said driver to said tooth or lug at any point to which the latter may have rotated with the platen, thereby to enable said driver to advance the platen to complete the cycle, and means for arresting the driver when said tooth or lug reaches the point which it occupied at the previous arrest of said driver; said driver being returnable to normal position while the platen remains stationary. 75
- 10 15 20 25 30 35 40 45 50 55 60 65 70 75 80 85 90 95 100 105 110 115 120 125 130
7. The combination with a revoluble platen, of means for rotating the same in instalments through a cycle of fixed extent, including line-spacing mechanism for making the initial instalments, and also including a driver for making the final instalment, and thereby bringing the platen always to the same predetermined position, irrespective of the extent to which the platen is initially advanced by the operations of the line-spacing mechanism; said driver being stationary at the operation of said line-spacing mechanism. 90
8. The combination with a revoluble platen, of means for rotating the same in instalments through a cycle of fixed extent, including line-spacing mechanism for making the initial instalments, and also including a driver for making the final instalment, and thereby bringing the platen always to the same predetermined position, irrespective of the extent to which the platen is initially advanced by the operations of the line-spacing mechanism; said driver being stationary at the operation of said line-spacing mechanism, and relatively adjustable stops being provided for limiting the stroke of said driver in both directions while the cycle remains fixed. 110
9. In a typewriting machine, the combination with a revoluble platen, of means for advancing the same through successive cycles, each consisting of a complete revolution, and for mechanically determining the point of completion of each cycle, comprising line-by-line feeding mechanism for giving the platen its initial movements from the starting point, a driver at rest during the advancing of the platen by said line-spacing mechanism, means to couple said driver to said platen at any point to which the latter may have rotated, thereby to enable said driver to advance the platen to complete the cycle, and means for arresting the driver when said platen reaches the point which it occupied at the previous arrest of said driver; said driver being returnable to normal position while the platen remains stationary, and means being dependent upon the return of the driver to normal position to withdraw the coupling device, to permit the advance of the platen while the driver remains stationary at the subsequent operation of said line-spacing mechanism. 75
- 10 15 20 25 30 35 40 45 50 55 60 65 70 75 80 85 90 95 100 105 110 115 120 125 130
10. In a typewriting machine, the combination with a revoluble platen, of means for advancing the same through successive cycles, each consisting of a complete revolution, and for mechanically determining the point of completion of each cycle, comprising line-by-line feeding mechanism for giving the platen its initial movements from the starting point, a driver at rest during the advancing of the platen by said line-spacing mechanism, a tooth or lug rotating with the platen past said driver during such line-spacing movements, means to couple said driver to said tooth or lug at any point to which the latter may have rotated with the platen, thereby to enable said driver to advance the platen to complete the cycle, means for arresting the driver when said tooth or lug reaches the point which it occupied at the previous arrest of said driver; said driver being returnable to normal position while the platen remains stationary, and a fixed device to intercept said coupling member to withdraw it from the path of said tooth or lug. 90
11. In a typewriting machine, the combination with a rotary platen, of mechanism for effecting mechanically limited cycles of platen movements, each cycle being a complete single revolution of said platen, comprising line-spacing mechanism for effecting initial movements of the platen, and also comprising a driver for completing the advance of the platen through its cycle; said platen being rotatable by said line-spacing mechanism while said driver is at rest, devices for coupling the driver to the platen; said coupling devices effective at any point to which the platen may have been rotated by said line-spacing mechanism, whereby said driver is enabled to complete the cycle of the platen movements, means for arresting the driver at the completion of the revolution of the platen, and a spring for returning the driver while the platen remains stationary, said coupling devices being constructed to permit the independent return movement of the driver and the advance of the platen past the driver. 110
12. In a typewriting machine, the combination with a revoluble platen having a shaft, of a device fixed to the shaft and having a single tooth or lug, and means for re- 130

- volving the platen through successive pre-defined cycles, each consisting of an entire revolution, said revolving means including line-spacing means for giving the platen initial movements, and also including a driver having means to engage said single tooth or lug to bring the same to a fixed position at each operation of said driver; said single tooth or lug being movable past said driver
- 10 at the initial operations of said platen effected by said line-spacing mechanism.
13. In a typewriting machine, the combination with a revoluble platen, of means for giving the same successive predefined cycles of movements, each cycle consisting of a complete revolution, said means comprising line-spacing mechanism for effecting movements of the platen at the initial portion of its cycle, and also including a single tooth or lug having a fixed connection to the platen, and a driver to drive the platen by means of said tooth or lug; said platen being rotatable by said line-spacing mechanism while the driver is at rest; a dog caused by said driver to pick up said tooth or lug at any point to which the platen may have been advanced by said line-spacing mechanism, and thereby couple the platen and driver for completion of the cycle of the platen by said driver; separate stops to limit the advance and return strokes of the driver; the latter being returnable while the platen remains stationary; and a stationary support to which said stops are connected; said support having a cam for withdrawing said dog at the completion of the return movement of the driver, to permit said tooth or lug to pass said dog at the initial movements of the platen in its next cycle.
- 40 14. The combination with a revoluble
- platen, of means for advancing said platen in instalments through a fixed cycle amounting to exactly an entire revolution; said platen-advancing means comprising line-spacing mechanism for giving the platen *ad libitum* step-by-step movements to constitute the initial instalments in said cycle, and also comprising a driver stationary during such step-by-step movements, means to limit the stroke of said driver in both directions, and means to enable the driver in moving from one end to the other of its fixed stroke, to make the final instalment, of variable length, thereby to complete the cycle of movements of said platen.
15. The combination with a revoluble platen, of means for advancing said platen in instalments through a fixed cycle amounting to exactly an entire revolution; said platen-advancing means comprising line-spacing mechanism for giving the platen *ad libitum* step-by-step movements to constitute the initial instalments in said cycle, and also comprising a driver stationary during such step-by-step movements, means to limit the stroke of said driver in both directions, means to enable the driver in moving from one end to the other of its fixed stroke, to make the final instalment, of variable length, thereby to complete the cycle of movements of said platen, and a feed-roll to run upon said platen to coöperate with said platen-advancing means, by both feeding and releasing during each such cycle a work-piece which is too short to extend entirely around the platen.
